UNITED STATES PATENT OFFICE.

THOMAS H. BULLOCK AND THOMAS H. BULLOCK, JR., OF NEW YORK, N. Y.

HOLDING DEVICE.

Application filed July 11, 1925. Serial No. 42,870.

Our invention relates to improvements in holding or fastening devices, and more particularly is adapted for use in connection with shade or globe holders for lighting fixtures, and is illustrated in the accompanying drawings in that association, though it will be readily understood that the invention is not limited thereto.

Referring to said drawings, Fig. 1 illustrates in side elevation, parts being broken away, a suitable form of shade holder with shade attached, the same embodying an application of our invention. Fig. 2 is a view looking upwardly at Fig. 1 with the globe removed. Fig. 3 is an enlarged detail looking upwardly at the rim of the shade holder, illustrating one form of our invention when in opened out position to release the globe. Fig. 4 is a similar view showing the same projected inwardly in locked position. Fig. 5 is a similar view illustrating a modified form of the device. Fig. 6 illustrates the same in inwardly projected position, and Fig. 7 is a fragmentary side view on an enlarged scale.

8 indicates a suitable form of shade or globe holder in conventional bell-like formation, and 9 the shade or globe suspended therefrom. The shade holder is preferably made of thin sheet metal such as brass, and is provided with a depending flange having an internal circumferential groove or channel 10, within which may be secured suitable resilient projecting members 11 for supporting the outwardly projecting flange or rim of the shade or globe. Opposite the said supports 11 may be secured springs 12 and 13, the former bearing upon the cam latch member 14, pivoted at 15, as shown, and the spring 13 projecting the button 16 as shown. When the shade has been introduced into the holder and rests upon the supports 11, the cam latch 14 is pushed from left to right looking at Figs. 2, 3, and 4, thereby projecting the spring or holder 12 inwardly and causing the free end of the spring 13 to ride successively into the notches between the teeth 17 of the latch. The number of teeth traversed by the free end of the spring 13 will depend upon the diameter of the rim or flange of the shade or globe, a wide flange allowing the spring to only enter the first tooth. When it is desired to remove the globe or shade, it is only necessary to push inwardly upon the button 16

looking at Figs. 2, 3, and 4, thereby releasing the same from engagement with the teeth 17 and allowing the cam 14 to be rolled leftwardly, thereby disengaging the third support of the shade or globe and allowing the same to be removed.

In the modification shown in Figs. 5 to 7 inclusive, the cam is indicated by the reference character 18, and may be provided with teeth, as shown, being eccentrically mounted upon the pin as indicated at 19. In the position shown in Fig. 5, the holder is clear to receive the shade, and in the position shown in Fig. 6, the spring 12 of the holder has been thrown inwardly into supporting engagement with the rim of the shade or globe, securely holding the same in position, any slight variation in the diameter of the same being taken up by the resiliency in the spring 12. When the globe is to be removed, the lever 20 of the cam is thrown leftwardly from the position shown in Fig. 6 so as to lay flat against the rim of the shade holder as shown in Figs. 5 and 7.

If desired, the spring 12 may be eliminated entirely, and the enlarged projection of the cam 18 may be used for the support of the shade or globe rim, but in that case it may be found desirable to use a conventional form of spring for keeping the cam in normal position, or if desired, the lever cam 18 may be mounted with sufficient friction so as to remain in either position that it is thrown, thus simplifying and cheapening the attachment.

Of course it will be understood that various modifications may be made in the construction and arrangement of parts without departing from the spirit of the invention as claimed.

We claim:—

1. In a shade holder of the class described, a lower rim having two supports, and a third support adapted to be moved in and out of supporting position, said third support adapted to swing upon a substantially vertical axis, and of substantially cam-like formation, and a resilient member for engaging and disengaging said third member.

2. In a shade holder of the class described, a lower rim having two supports, and a third support adapted to be moved in and out of supporting position, said third support adapted to swing upon a substan-

tially vertical axis, and said third support of substantially cam-like formation, and provided with teeth adapted to be engaged for holding the same in adjusted position, and a resilient member for engaging and disengaging said teeth.

3. In a shade holder of the class described, a lower rim having two supports, and a third support adapted to be moved in 10 and out of supporting position, said third support adapted to swing upon a substantially vertical axis, and said third support

of substantially cam-like formation, and provided with teeth adapted to be engaged for holding the same in adjusted position, and a resilient member for engaging and disengaging said teeth, said resilient member provided with a button for operating the same. 15

In testimony whereof we hereunto affix 20 our signatures.

THOMAS H. BULLOCK.
